UNITED STATES PATENT OFFICE.

LUDWIG NUDL, OF WHITTLESEA, VICTORIA, AUSTRALIA, ASSIGNOR TO THE NUDL SAFETY CABINET TICKET TUBE COMPANY PROPRIETARY LIMITED, OF MELBOURNE, VICTORIA, AUSTRALIA, A COMPANY OF VICTORIA.

VENDING OF RAILWAY AND LIKE TICKETS.

Application filed July 10, 1922. Serial No. 573,852.

To all whom it may concern:

Be it known that I, Ludwig NUDL, a subject of the King of Great Britain and Ireland, and a resident of the postal district of Epping, in the shire of Whittlesea, in the parish of Toorourrong, county of Bourke, State of Victoria, Commonwealth of Australia, have invented certain new and useful Improvements relating to the Vending of Railway and like Tickets, of which the following is a specification.

This invention relates to the vending or delivery of tickets at railway stations and like public places and more particularly concerns means for storing and withdrawing tickets from ticket tubes or receptacles, such as those of the type commonly used at railway stations.

The primary object of the present invention is to provide reliable means whereby tickets may be stored and expeditiously withdrawn for delivery as required by a special push operated ejecting mechanism, which, by a simple pressing movement of the operator's hand causes the ticket to be ejected from the bottom of the stack in the receptacle and positioned between the thumb and forefinger of the hand by which it is thus readily withdrawn. The delivery of the tickets is thereby rendered much more simple and expeditious than with previous devices for the same purpose wherein it is usually necessary to pull out a slide which carries the ticket from the bottom of the stack.

A further object of the invention is to provide a simple and effective means of indicating the number of tickets in the respective stacks, thus providing a check on the removal and insertion of tickets in the stacks accommodated by the receptacle. The apparatus involved is, moreover, simple and inexpensive and may be readily applied to existing as well as to other suitable types of ticket tubes or receptacles.

Referring to the drawings which form part of this specification:

Figure 1 is a side sectional elevation taken through a ticket supply tube or compartment equipped with the invention. The push member for operating the ticket ejector is shown in its normal or outward position the ejector being consequently at the inner

end of its movement. Parts are broken away for convenience of illustration.

Figure 2 is a view similar to Figure 1 but showing the push member pressed inward to force a ticket out into position for withdrawal.

Figure 3 is a sectional plan of two ticket tubes in accordance with the invention and showing one of the ticket ejectors in its outward or ejecting position and the other in its inward or normal position. Parts are omitted for convenience of illustration.

Figure 4 is a front view of the apparatus, portions being broken away.

Figure 5 is a detail view of a removable front plate.

Figure 6 is a section on line A—A of Figure 5.

Figure 7 is a perspective view of a pivoted stop or pawl which prevents insertion of tickets at the bottom of the stack in the ticket compartment.

Figure 8 is a sectional plan of a push lever showing the arrangement of the controlling spring.

According to the invention the ticket cabinet or receptacle 2 is preferably closed at its back and two sides and is provided with an open front, a hinged top 3 and a hinged bottom 4, these latter hinged parts being retained in closed position by catches or fasteners 6 of any suitable construction.

The receptacle may be sub-divided into any desired number of vertical ticket compartments 7 by a partition or partitions 8.

Each ticket compartment 7 is closed at its lower end by a stationary platform 9 disposed at some little distance above the hinged bottom 4. This platform is removably mounted in horizontal grooves 10 in the walls of the ticket compartment and is provided on its upper surface with opposite upstanding lips 11 extending along its side edges and forming a guideway for the ejector hereinafter described. The front edge of the platform 9 has a semicircular gullet 15 therein to accommodate the thumb of the operator when withdrawing the ticket as hereinafter described.

Formed in the platform 9 beneath each ticket compartment are two parallel slots 12, through each of which passes a depending pin 13, these pins being attached at

their upper ends to a ticket ejector 14 which rests upon the platform 9. The depending pins 13 are united beneath said platform by a cross bar 16 and the upper face of the 5 ejector has at its rear end an upstanding shoulder or projection 17 which engages behind the rear of the lowermost ticket in the stack and causes it to be ejected on manipulation of the push lever hereinafter 10 described.

Accommodated within the space or chamber between the platform 9 and the hinged bottom 4 is the ejector operating mechanism which preferably comprises a link 18 15 pivoted at its rear or inner end to one of the aforesaid depending pins 13. Pivoted to the front end of said link 18 is a lever 21 which is intermediately pivoted to a pivot pin 22 depending from the aforesaid platform. The other end of the lever 21 is pivotally connected by an arm 23 with a push member preferably in the form of a lever 24 which is pivoted at its lower end to a cross pin 26 extending across the front of 20 the apparatus near the lower hinged bottom. 25

The cross pin 26 is removably mounted in open mouthed recesses 27 which are formed in the lower edge of a detachable front plate 30 28. This plate is attached to the front of the ticket receptacle at its lower end by screws 29 so that by taking off the front plate access may be had to the working parts 35 which may also be removed bodily with the platform 9 for inspection or repair.

The detachable front plate 28 is provided, opposite each ticket compartment, with a ticket delivery aperture 31 through which the front end of the respective platform 9 passes. 40 Extending over each said aperture is a forwardly projecting guard portion or hood 32 having in its front edge a semicircular thumb gullet 33 corresponding to the gullet 15 of the platform 9. The object of the forwardly projecting guard portion or hood 32, 45 which constitutes a feature of the invention, is to prevent unauthorized manipulation of the pawl hereinafter described for obviating fraudulent insertion of or interference with 50 the tickets at the bottom of the stack.

The aforesaid push lever 24 is normally pressed outwards and the ejector inwards by means of a coiled spring 34 encircling the aforesaid cross pin 26 between two opposite 55 upstanding side lugs 36 on the push lever, which latter is preferably of substantially channel shape in cross section, as seen in Figure 8, and has at its top a bridge portion 37 extending between said side lugs 36. One 60 end 38 of said spring 34 presses against the push lever and thus normally forces the ticket ejector inwardly beneath the stack of tickets in the respective ticket compartment as in Figure 1. This transverse arrangement 65 of the spring, whereby it is wound up by

inward pressure on the push lever and unwound on the return movement of the ejector, constitutes a feature of the invention as it renders the spring much less liable to weaken and consequently more reliable than 70 if an ordinary tension or compression spring were employed to return the ejector.

When in normal position the push lever is inclined outwardly from its lower to its upper end as in Figure 1, the lever being 75 pressed inwardly through an opening 39 in the front plate 28 between the platform 9 and the lower hinged bottom 4.

To prevent unauthorized insertion of spurious or other tickets at the bottom of the 80 stack without obstructing the ejection of the tickets, a suitable non-return device is employed. This preferably consists of a pawl 41 pivotally mounted at the lower end of each ticket compartment. This pawl extends across the front of the compartment immediately above the platform 9 and is provided at its ends with trunnions or pivots 42 mounted in bearings 43 at the sides of the ticket compartment. The pawl is preferably 85 pressed downwards against the platform 9 by a spring 44 and it is effectively guarded against fraudulent manipulation by reason of the forwardly extended hood or guard portion 32 over the ticket delivery aperture 31. 95

The front of each ticket compartment above the platform 9 may be closed by a removable indicating plate 46 having a vertically elongated central slot or opening 47 and graduations 48 along the edge of said opening. 100 The spacing of these graduations preferably corresponds to the thickness of the tickets so that by means of the pointer hereinafter described an exact indication of the number of tickets in each compartment is always 105 provided.

Resting upon the stack of tickets 49 in each ticket compartment is a weight 51 having an indicator or pointer 52 which projects through the elongated opening 47 in the removable plate 46 and thus provides a permanent and instant indication of the number of tickets in the stack, consequently 110 serving as a safeguard against fraud.

A ticket ejecting and indicating mechanism as above described is provided for each of the ticket compartments, any desired number of which may be provided in the one receptacle or cabinet. 115

In use, the hinged top of the cabinet is 120 opened and a stack of tickets is placed in each compartment 7. The weight 51 is placed on the top of the tickets in each compartment with the indicator 52 projecting through the vertically elongated opening 47 in the removable plate 46. The hinged top is then closed and locked. To obtain a ticket the operator presses the push lever 24 inwardly with the bent forefinger as indicated in Figure 1. This causes the ejector 125 130

to be forced outwardly through the medium of the lever and link mechanism beneath the platform 9. The lowermost ticket of the stack is thus ejected and positioned as in

the push lever with the ejector whereby the latter is moved outwardly by inward pressure on the push lever, for the purpose set forth.

- 5 Figure 2 between the thumb and forefinger, by which it is thus conveniently seized and withdrawn. By the foregoing arrangement the delivery of the tickets is rendered extremely simple and expeditious and it is
 10 impracticable to insert into or fraudulently manipulate tickets at the bottom of the ticket compartment owing to the presence of the non-return device 41 and the extended hood or guard portion 32.
 15 Immediately on removal of the pressure from the push lever the ejector returns to its normal or inward position and the next ticket in the stack drops in front of the upstanding shoulder or projection 17, to be
 20 ejected by the next operation of the push lever.

The weight 51 and the pointer 52 thereon fall as each ticket is removed and thus indicates by the graduations on the indicating plate 46 whether any and what number of tickets have been removed from or inserted in each compartment. If desired, however, the slotted and graduated indicating plate and the pointer may be dispensed with and
 30 a removable plate, provided with small observation holes arranged one above the other to disclose the height of the ticket stack may be employed in lieu thereof.

Having now described my invention what
 35 I claim as new and desire to secure by Letters Patent is:—

1. A ticket delivery apparatus consisting in the combination with a ticket receptacle having one or more compartments each
 40 adapted to contain a stack of tickets, of a ticket ejector disposed at the bottom of each compartment, a spring controlled push lever adapted to actuate said ejector, said push lever being pivoted at its lower end
 45 on a transverse axis and having its upper travelling end disposed beneath and adjacent the point where the tickets are ejected from the receptacle, and means operatively connecting said push lever with the ejector
 50 whereby the latter is moved outwardly by inward pressure on the push lever, for the purpose set forth.

2. A ticket delivery apparatus consisting in the combination with a ticket receptacle
 55 having one or more compartments each adapted to contain a stack of tickets, of a ticket ejector disposed at the bottom of each compartment, a spring controlled push lever adapted to actuate said ejector, said push lever being provided with opposite side cheeks and mounted on a transverse pivot pin which passes through said cheeks, said controlling spring being disposed between the side cheeks and encircling said
 60 pivot pin, and means operatively connecting

3. A ticket delivery apparatus consisting in the combination with a ticket receptacle having one or more compartments each adapted to contain a stack of tickets, of a ticket ejector disposed at the bottom of each compartment, a spring controlled 70 pivoted push lever adapted to actuate said ejector, said push lever being mounted on a transversely disposed pivot pin which is encircled by said controlling spring, and a removable front plate attached to the front of the ticket receptacle at its lower end, said front plate having open-mouthed recesses at its lower edge to accommodate the transverse pivot pin of the push lever, and also having an opening through which said 80 push lever moves substantially as described.

4. A ticket delivery apparatus, comprising, in combination, a receptacle provided with a compartment to contain a stack of tickets having a horizontal platform at its bottom; an ejector mounted for bodily sliding movement on said platform and on which the ticket stack rests; a depending element secured to said platform; a lever pivoted intermediate its ends on 90 said element; a link connection between one end of the lever and the ejector; an inwardly-movable push member; and a link connection between said member and the other end of said lever, whereby the ejector will be slid bodily forward and outward 95 when the push member is pressed inward.

5. In a ticket delivery apparatus, the combination of a receptacle provided with a compartment to contain a stack of tickets; 100 an ejector for the tickets; a front plate attached to the lower portion of the receptacle and provided with a delivery aperture for the tickets and with a second aperture directly below the first one; a member normally projecting outward through the second aperture but adapted to be pushed inward therethrough by pressure exerted against it by the forefinger of one hand of the operator to effect the outward movement of the ejector; and a forwardly-extending guard disposed above the ticket 110 aperture and overhanging the projecting portion of the operating member, said guard having its forward end cut away to expose the projecting end of the ticket 115 acted on by the ejector, whereby said projecting ticket end may be grasped between the thumb and forefinger of the same hand and removed.

In testimony whereof I affix my signature.

L. NUDL.
